UNITED STATES PATENT OFFICE.

FREDERICK STITZEL, OF LOUISVILLE, KENTUCKY.

GOVERNOR.

1,122,328.

Specification of Letters Patent.

Patented Dec. 29, 1914.

Application filed April 6, 1914. Serial No. 829,921.

To all whom it may concern:

Be it known that I, FREDERICK STITZEL, a citizen of the United States, residing at Louisville, in the county of Jefferson and State of Kentucky, have invented a certain new and useful Improvement in Governors, of which the following is a full, clear, and exact description.

This invention relates to governors for steam engines, and particularly to steam engines of the type having no rotary motion, such as steam pumping engines.

The object of the invention is to provide an efficient governor which can be applied to any engine of the type specified, and which may be set to cause the engine to operate at any predetermined speed and maintain such speed automatically.

The invention comprises a reciprocating rod which receives motion by means of a steam or a mechanical or other connection with the working parts of any suitable engine, and cooperates with a pivoted and weighted arm through the intervention of a peculiar pawl and ratchet mechanism to regulate the supply of motive fluid, as I will proceed now to explain and finally claim.

In the accompanying drawings illustrating the invention, in the several figures of which like parts are similarly designated, Figure 1 is a side elevation showing the invention applied to a steam pumping engine, and in which the governor is operated by steam. Fig. 2 is a view similar to Fig. 1 but showing the governor mechanically operated. Fig. 3 is a front view of the governor with one of the bearings of the weighted arm broken away. Fig. 4 is a section taken in the plane of line A B, Fig. 5. Fig. 5 is a side elevation and showing the connection between the governor and the steam valve. Figs. 6, 7 and 8 show different positions of a portion of the devices for operating the weighted arm and toothed disk, the relative positions of the weighted arm being shown in dot and dash lines. Fig. 9 is a section showing a modification in which the governor is operated by steam with the aid of a spring. Fig. 10 is a section similar to Fig. 4, taken substantially through the center of the governor and showing the operating mechanism of Fig. 2. Figs. 11 and 12 are respectively, a cross-section and a front elevation showing a modification of

the construction of Fig. 2, wherein the return spring is dispensed with.

1 is the steam cylinder, 2 the water cylinder, 3 the steam chest, 4 the piston rod, 5 the valve rod, and 6 the steam pipe of an ordinary steam pump.

The governor has a supporting frame 7 secured to the steam chest of the engine, and this frame has the back plate 8 with transverse bearing pieces 9 and 10, and to these bearing pieces is secured a front plate 11, as by means of screws 12 (Fig. 3). Slidably mounted in the bearing pieces 9 and 10 is a vertical rod 13 having at its upper end a head 14 upon which is pivotally mounted a double pawl 15 to which is rigidly secured an arm 16 having a horizontally extending contact finger 17. The pawl 15 is overbalanced at one end 18 and a suitable stop 19 is provided to limit its downward movement. At the left-hand side of the head 14 is an off-standing contact piece 20 upon the outer end of which is mounted a spring 21 under which the finger 17 is adapted at times to be frictionally held as will be hereinafter described. Mounted in bearings in the plates 8 and 11 above the pawl 15 is a toothed disk 22 suitably connected, as by a slot and pin connection 23, with the stem 24 of an ordinary globe or other steam valve 25 which is interposed in the steam pipe 6 to control the admission of steam to the engine. This disk 22 is turned in one direction or the other to open or close the valve 25 by means of the contact with it of the pawl 15. In one form of the invention, illustrated in Figs. 1, 3, 4, and 5, the lower end of rod 13 is so constructed as to form a piston rod 26 and piston 27 operating within a small cylinder 28 having two steam inlets, one 29 above the piston and one 30 below the piston, and these inlets are connected by pipes 31 and 32, respectively, with the steam ports leading to the opposite ends of the steam cylinder of the pump or other engine, as shown in Fig. 1.

Between the front plate 11 and a bearing piece 33 is an arm 34, loosely mounted upon a shaft 35 which is supported in said front plate and bearing piece. At the rear of the arm 34 and fixed upon the shaft 35 is a serrated-faced disk 36 which is adapted to engage a pair of teeth 37 and 38 (Fig. 5) carried by the arm, so that said arm may be angularly adjusted on the shaft 35 with re-

lation to the fingers next described. The outer end of the shaft 35 is screwthreaded and provided with a nut 39 (Fig. 3) so that when the required adjustment has been made, the parts may be maintained in fixed relation. Carried by the disk 36 is a pair of contact fingers 40 and 41. The finger 40 is operated upon by the contact piece 20, as the rod 13 and its head 14 carrying piece 20 move up and down due to the pulsations of the steam in cylinder 28, to move the arm. The finger 41 acts upon the finger 17 to bring it to upright or neutral position, or to cause it to be engaged by spring 21 as will be described. The arm and all of its connections are entirely separate from the reciprocating rod and its connections, the communication between them being effected by means of the parts 17, 20, 40 and 41. The upper part of the arm 34 is provided with a weight 42 preferably made in halves, one of which is fixed to the arm and the other hinged to said fixed half, as at 43, and separably connected therewith at a point opposite the hinge-joint by a bolt and nut or other connection 44. Stops 45 are provided on the halves at their hinge-joint, so as to limit the extent to which the movable half may fall away from the fixed half. I have found that the greatest variations per minute may be obtained by placing the shorter part of the arm and the heavier weight at the top and start the drop near the vertical and let it end somewhat below the horizontal. When the drop is slow, the momentum is not sufficient to operate the pawl, and in order to correct this difficulty the connection 44 is released and the movable half of the weight 42 is therefore free to fall away from the fixed half when the arm passes the horizontal and thereby impart the required momentum. The movable half of the weight automatically returns to position on the fixed half as the arm returns. The lower and longer part of the arm is screwthreaded throughout its length and provided with a weight 46, which may be adjusted toward the pivot to increase the velocity of the drop of the arm or away from the pivot to retard the velocity of the drop, so that the pump may be run at different speeds. This weight may be lighter than weight 42, and it may be secured in adjusted position by a jam-nut 47.

In the modification shown in Fig. 9, a single steam inlet 48 only is provided in the cylinder 49, and in order to return the rod 13 when the steam is exhausted from cylinder 49, there is provided a spring 50 acting against bearing piece 9 and a collar 51 on rod 13. Aside from this the mechanism is the same as in the previously described form.

In the modification shown in Figs. 2 and 10, the bracket 7 is dispensed with and a

plate 52 having an opening 53 is substituted for securing the governor to the steam chest. Furthermore, a reciprocating cam bar 54 is provided, one end of which slides in the opening 53 and the other end of which is connected by an arm 55 with the valve rod 5, whereby it is reciprocated. The cam surface 56 of the bar 54 is adapted to engage the beveled end of rod 13 in order to move it up, and it is forced down, when the cam surface 56 is retracted, by means of a spring 57.

The modification shown in Figs. 11 and 12 is similar to that last described, the difference being that in this the cam bar 58 is double-faced and the rod 13 is perforated at 59 to allow the bar to slide through it, thus positively moving rod 13 up and down and dispensing with the spring 57.

Referring particularly to the form of the invention illustrated in Figs. 1, 3, 4 and 5, the operation is as follows:—The engine being at rest, the arm 34 will be in its lowermost position and it and the pawl and associated parts will be in the position shown in Fig. 7. When steam is turned on it will enter the left-hand end of cylinder 1 and through pipe 32 will enter the lower end of cylinder 28 to push up the piston 27 and rod 13. Contact piece 20 will therefore push up on finger 40 thus raising arm 34 until its threaded portion comes in contact with stop 60 and will hold it there until the piston in cylinder 1 has reached the end of its right-hand stroke. Then the spent steam will exhaust from the left-hand end of cylinder 1 and lower end of cylinder 28 and live steam will enter the right-hand end of cylinder 1 and upper end of cylinder 28, and the piston in cylinder 1 will be moved back to the left and piston 27 and rod 13 will be moved down, thus releasing arm 34 so that it may drop from the position shown in Fig. 3, turning with it its shaft 35 and the disk 36 with contact fingers 40 and 41. But when the head 14 was in its uppermost position, pawl 15 was brought in contact with toothed disk 22 and the finger 17 was released from spring 21 so that when head 14 dropped when piston 27 was pushed down, the overbalanced end 18 of pawl 15 dropped against stop 19 and the left-hand point of the pawl was up, which is the position for closing the valve.

Before arm 34 reaches the limit of its drop, the finger 40 will be engaged by the contact piece 20, which is rising with head 14 of rod 13, due to another upward pulsation in cylinder 28, and as the upward motion of contact piece 20 is very rapid, it will engage finger 40 with considerable force, thus throwing up arm 34 until its screwthreaded portion strikes against stop 60 again. The drop of the arm 34 besides bringing finger 40 in contact with piece 20

also causes finger 41 to engage finger 17 to bring pawl 15 to a position where its two points are in horizontal alinement. This position as regards the parts 14, 15, 17 and 5 41 which is the same as that where the piece 20 is just engaging finger 40 is clearly illustrated in Fig. 8. The points of the pawl 15 being in horizontal alinement and the head 14 very near the end of its up stroke, the 10 two points of the pawl will come in contact with the toothed disk 22 simultaneously as shown in dotted lines in Fig. 9, and thus fail to turn it in either direction.

The description in the last preceding paragraph applies when the operations of the pump and governor are synchronous.

It takes several strokes of the pump in starting to make the operations of the pump and governor synchronous. In case the 20 pump runs too fast, then contact piece 20 will be forced up earlier during the fall of arm 34 and will throw arm 34 up sooner than in the previous instance, and the overbalanced end 18 of the pawl 15 will drop 25 so as to present the left-hand point uppermost for engagement with a tooth on the toothed disk 22 to turn it to close the valve. In case the pump runs too slow, the arm 34 will fall to the limit of its drop and the 30 finger 41 will push finger 17 under spring 21, as shown in Fig. 7, and then when head 14 rises and again pushes up arm 34, the right-hand point of pawl 15 will be held uppermost because of the frictional hold of 35 spring 21 on finger 17, and when this point of the pawl comes into engagement with a tooth on disk 22, it will turn the disk to open the valve. It will thus be seen that a constant speed of the engine or pump may be 40 maintained.

The operation of the other forms of the invention herein shown and explained is the same in all material respects as that just set forth, except for the manner of reciprocating rod 13 as hereinbefore stated.

The invention has been herein shown as applied to horizontal pumps or engines, whereas it may be applied to vertical pumps and engines equally well, and in that case 50 the overbalanced end 18 of the double-pointed pawl 15 may be omitted, because the arm 16 and finger 17 will act as an overbalance. These and other variations are within the principle of the invention and the 55 scope of the claims herein.

What I claim is:—

1. In a governor for steam engines and the like, a steam pipe for supplying steam to said engine, a controlling valve in said pipe, a weighted arm raised by said engine and falling by gravity, and means interposed between said falling arm and the valve to move the valve in opposite directions to control the supply of steam to the 60 engine.

2. In a governor for steam engines and the like, a steam pipe for supplying steam to said engine, a controlling valve in said pipe, a falling arm operated by the engine, and means interposed between said arm and valve to rotate the stem of said valve in opposite directions to control the supply of steam to the engine. 70

3. In a governor for steam engines and the like, a steam pipe for supplying steam to said engine, a controlling valve in said pipe, a falling arm pivoted between its ends so as to have a shorter and a longer portion, a fixed weight on its shorter portion, and an adjustable weight on its longer portion 80 lighter than the fixed weight, whereby the balance of said arm may be varied to regulate the velocity of its fall, and means interposed between said arm and valve to rotate the stem of said valve in opposite directions to control the supply of steam to 85 said engine.

4. In a governor for steam engines and the like, a steam pipe for supplying steam to said engine, a controlling valve in said pipe, a falling arm operated by the engine, and means comprising a toothed disk and a pawl carried by a reciprocating rod interposed between said arm and valve to rotate the stem of said valve in opposite directions to control the supply of steam to said engine. 90

5. In a governor for steam engines and the like, a steam pipe for supplying steam to said engine, a controlling valve in said pipe, a pivoted and weighted arm, means comprising a rod reciprocated by the engine for operating said arm, a toothed disk mounted upon the stem of said valve, and a pawl carried by said rod and operated by 100 said arm to bring it into proper position when necessary to engage said disk to rotate the stem of said valve in opposite directions to control the supply of steam to 105 said engine. 110

6. In a governor for steam engines and the like, a steam pipe for supplying steam to said engine, a controlling valve in said pipe, a pivoted arm operated by the engine, said arm having a partible weight on its shorter portion, and means interposed between said arm and valve to rotate the stem of said valve in opposite directions to control the supply of steam to the engine. 115

7. In a governor for steam engines and the like, a steam pipe for supplying steam to said engine, a controlling valve in said pipe, a pivoted arm, means comprising a rod reciprocated by the engine for operating said arm, a toothed disk mounted upon the stem of said valve, and a double-pointed pawl pivotally mounted upon said rod and adapted to engage said disk. 120

8. In a governor for steam engines and the like, a steam pipe for supplying steam 130

to said engine, a controlling valve in said pipe, a pivoted arm, means comprising a rod reciprocated by the engine for operating said arm, a head on the upper end of 5 said rod, a double-pointed pawl pivotally mounted on said head and having a projecting finger adapted to be operated by said arm, a spring mounted upon said head and adapted to frictionally engage said finger 10 to hold said pawl in one operative position, and a toothed disk mounted upon the stem of said valve and adapted to be engaged by said pawl when said rod reciprocates, whereby the stem of said valve may be rotated in 15 opposite directions to control the supply of steam to said engine.

9. In a governor for steam engines and the like, a steam pipe for supplying steam to said engine, a controlling valve in said 20 pipe, a frame for said governor whereby it is mounted upon said engine, an arm loosely mounted upon a shaft supported in said frame, a serrated-faced disk fixedly mounted on said shaft, a pair of contact fingers

carried by said disk, teeth on said arm 25 adapted to engage the serrations on the face of said disk, whereby the angular relation of the arm to said contact fingers may be varied, a reciprocating rod having a head which carries a contact piece adapted to engage one of the contact fingers on said serrated-faced disk, a double-pointed overbalanced pawl pivotally mounted on said head and having a contact finger adapted to be engaged by the other contact finger of said 30 serrated-faced disk, and a toothed disk mounted upon the stem of said controlling valve and adapted to be engaged by said pawl, whereby it may be rotated in opposite directions to operate the valve and control the supply of steam to said engine. 35

In testimony whereof I have hereunto set my hand this 4th day of April, A. D. 1914.

FREDERICK STITZEL.
